UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,121,127.

Specification of Letters Patent.

Patented Dec. 15, 1914.

Application filed April 5, 1905. Serial No. 254,012.

To all whom it may concern:

Be it known that I, LANSING ONDERDONK, a citizen of the United States, residing at New York, in the county of New York, State of New York, have invented certain new and useful Improvements in Feeding Mechanism for Sewing-Machines, of which the following is a description, reference being had to the accompanying drawings and 10 to the letters and figures of reference marked thereon.

This invention relates to sewing machines, and particularly to machines of that class employed in the sewing of knit fabrics, 15 where it is essential to compensate for the stretching action of the usual feeding devices.

In the sewing of knit goods, the feed dog and presser foot exercise a flattening and 20 stretching action on the goods, and there is more or less puckering of the finished article.

The principal object of the present invention is to prevent this stretching and 25 puckering by fulling or crowding the fabric in advance of the needle.

A further object of the invention is to 30 provide a feed mechanism of such construction that the rate of feed at the front or entrance end will be in excess of that at the discharge end.

A still further object of the invention is 35 to provide a novel form of feed dog, in which the fabric-engaging surface is of such character as to exercise feeding action of different character, or of different effectiveness, at different points in its length.

A still further object of the invention is 40 to provide a feed dog having a retarding surface arranged between positive or ser- rated feeding surfaces.

A still further object of the invention is 45 to provide a feed dog having its upper surface inclined upward toward the front or entrance end, and provided with a group of preliminary or fulling feed serrations, and having at its rear and lower end a series of serrations or teeth to effect discharge of the fabric from engagement with the presser foot.

50 With these and other objects in view, as will more fully hereinafter appear, the invention consists in the novel construction and arrangement of parts hereinafter described, illustrated in the accompanying drawings and particularly pointed out in

the appended claims, it being understood that various changes in the form, proportions and minor details of construction of the apparatus may be made without departing from the spirit or sacrificing any of the advantages of the invention.

In the accompanying drawings, Figure 1 is a transverse sectional view of sufficient of a sewing machine to illustrate the invention; Fig. 2 is a detail elevation of the feed 65 dog and presser foot on an exaggerated scale; Fig. 3 is a detail perspective view of the feed dog; Fig. 4 is a transverse sectional view of the machine looking in the direction opposite to that shown in Fig. 1, and 70 showing more of the mechanical details; and Fig. 5 is a transverse section of the feeding mechanism and the throat plate.

A is the bed of the machine; B, the driving shaft; C the feed rocker, the parts being 75 actuated in the usual way from a crank pin on the end of the driving shaft and the cam on the driving shaft imparting the vertical movement to the dog, as usual.

The feed dog F is mounted in any suitable manner, as, for instance, in the manner shown in the patent granted to R. G. Woodward, October 24th, 1903, #802,789, and its upper or feeding surface is arranged at a slight angle to the horizontal, the outer end 85 being the highest so that it will engage with the fabric in advance of the rear portion of the dog, and thus full or crowd the fabric toward the needle, the feed being faster at the front than at the discharge end in order 90 to prevent the stretching and consequent puckering of the goods, as previously pointed out.

The feeding teeth or serrations are arranged in two spaced groups, one, 10, at the 95 front and higher end of the dog, and the other 11, at the lower and rear end of said dog, and the front serrations are extended back to a point to the rear of the needle n, to hold the fabric gathered or fulled until 100 it has been stitched down. Between the rearmost of the front group of serrations, and the first of the rear group is a smooth or untoothed surface 12, which is preferably in the plane of the points or crowns of the 105 teeth, and acts as a retarder to prevent the goods feeding freely back of the needle, the device acting practically as two independent feed dogs, spaced by a retarding means.

Owing to the inclination of the feed dog, 110

the group of serrations 10 in advance of the needle moves the fabric ahead until it reaches the untoothed or smooth surface 12, which retards movement of the fabric, and 5 by holding the same permits the forward end of the dog to full in said fabric, and prevents the rear group of teeth from feeding the fabric beyond the heel of the presser foot at the same speed.

10 In the rising and forward movement of the feed dog the front group of teeth will be elevated above the plane of the throat plate before the smooth portion of the feed dog and before the rear group of teeth, that 15 is to say in the cycle of operation the front teeth engage the fabric first and the smooth surface engages the fabric subsequently to the engagement thereof by the front teeth and likewise the rear teeth engage the 20 fabric subsequently to the engagement thereof by the smooth surface. This is due to the fact that the feed dog is inclined to the horizontal and the front teeth are always above the smooth surface and the smooth 25 surface is above the rear teeth of the feed dog, and the feed dog is raised vertically into engagement with the fabric. This movement of the feed dog will cause the front teeth to push the fabric on to the 30 retarding surface and the fabric will thus be fulled or gathered and the stitches will pass through the gathered portion. I have referred to the action of the smooth surface of the feed dog as a retarding action 35 because it clamps the goods against the presser foot and being a non-feeding surface, it will cause a friction holding back the fabric to assist in gathering it in front of the needle and also to prevent too free 40 moving of the fabric by the rear portion of the feed dog.

Having thus described my invention, what I claim as new, and desire to secure by Letters Patent, is:—

45 1. A sewing machine, including in combination, a needle, feeding mechanism, means for causing said feeding mechanism to feed the material in advance of the needle faster than in rear thereof, said feeding mechanism having a toothed portion engaging the 50 material in advance of the needle, and a

smooth material engaging retarding portion directly in rear of the toothed portion and engaging and movable horizontally with said material subsequent to the engagement thereof by the toothed portion. 55

2. A sewing machine including in combination, a cloth plate, a feed dog which is inclined from the front end thereof toward the rear relative to said cloth plate, whereby 60 the front portion of said feed dog is adapted to engage the material in advance of the remaining portion thereof, said feed dog having a toothed portion at the front end thereof, and a plane portion directly in rear 65 of the toothed portion, the upper surface of said plane portion being substantially in line with the crown of the toothed portion. 70

3. A sewing machine including in combination, a cloth plate, a needle, a feed dog inclined from front to rear relative to said cloth plate and having two groups of fabric engaging serrations located one in advance 75 of the other, the front group of serrations being located in front of the needle and extending to, or beyond the same, said groups of serrations being divided by a non-fabric feeding portion, the front group of serrations being so disposed relative to the rear group of serrations as to engage the material in advance thereof. 80

4. In a sewing machine a feed dog having its feeding face inclined upward toward the front end with respect to the cloth plate of the machine and provided with 85 front and rear groups of teeth or serrations, divided by a blank space disposed in the plane of the crowns of the teeth; substantially as described.

5. In a sewing machine, including a 90 needle, a feed dog inclined with respect to the cloth plate having front and rear feeding surfaces separated by a non-feeding surface, the vertical plane of movement of the needle being in advance of the non-feeding surface; substantially as described. 95

In testimony whereof I affix my signature, in presence of two witnesses.

LANSING ONDERDONK.
